UNITED STATES PATENT OFFICE.

EMMERICH H. KRISTEK, OF NORTH GROSVENOR DALE, CONNECTICUT, ASSIGNOR TO DRAPER COMPANY, OF HOPEDALE, MASSACHUSETTS, A CORPORATION OF MAINE.

BUILDER-MOTION.

1,139,877.

Specification of Letters Patent.

Patented May 18, 1915.

Application filed November 21, 1914. Serial No. 873,277.

To all whom it may concern:

Be it known that I, EMMERICH H. KRISTEK, a citizen of the United States, residing at North Grosvenor Dale, county of Windham, and State of Connecticut, have invented an Improvement in Builder-Motions, of which the following description, in connection with the accompanying drawings, is a specification, like letters on the drawings representing like parts.

The invention to be hereinafter described relates to spinning machines for spinning and winding yarn onto carriers or bobbins, and more particularly to the builder motion in such machines whereby the desired character of wound bobbins or carriers is produced.

In some types of filling replenishing looms, it is desirable that the wound bobbins or carriers used for laying the filling shall be provided with preliminary or initial windings to coöperate with certain mechanism of the loom to cause filling replenishment only when the filling on the bobbin or carrier in use has become practically exhausted. When the carrier or bobbin to be abandoned is ejected from the shuttle, it still contains some windings of filling which constitute waste and must be removed from the carrier or bobbin before it can be again supplied with a load of filling. It is of importance, therefore, that the preliminary or initial windings, which are frequently called "a bunch", shall be so placed upon the bobbin or carrier that the amount of waste shall be reduced to a minimum and yet the bobbin or carrier be supplied with the maximum load.

Many attempts have been made to carry into effect these desirable characteristics, among the most simple and successful of which is that of Charles E. Lovejoy, as described and claimed in his application, Serial No. 780,863, filed July 24, 1913, where-in a deflector was attached to the flexible connection between the builder motion and ring-rail and caused to act in a manner to secure a proper form of initial windings or bunch. The simplicity of this device, its adaptability for ready application, and its effectiveness in operation, have dictated its incorporation in the well-known Howard & Bullock type of spinning machine; but owing to the character of this type of spinning

machine, the Lovejoy device could not be applied.

With these matters in view, the aims and purposes of the present invention will best be made clear from the following description and accompanying drawing of one practical form or embodiment of the invention, it being understood that it is not restricted to the particulars and details shown, but that it may be varied within the true scope of the invention, as set forth by the claims.

In the drawings:—Figure 1 is a perspective view of sufficient portions of a spinning frame, builder motion, and ring-rail connections to make clear the present invention; Fig. 2 is a diagrammatic view showing the connections between the builder motion and ring-rail; Fig. 3 is a side elevation of a wound bobbin or carrier having a bunch, as shown by dotted lines.

Pivotedly mounted at 1 upon a suitable support or the machine frame, is the builder motion frame comprising the upright arm 2 and side arm 3, the latter of which has the extension 4 jointed thereto at 5, and provided with a roll 6 to bear upon a cam by which the builder motion frame may be rocked about the pivotal mounting 1. An adjusting screw 8 serves to define the relation of the arms 3 and 4 and to transmit the downward motion of the arm 4 through the arm 3 to the builder frame.

Mounted on a shaft 9 extending transversely of the builder frame, is the ratchet or pick wheel 10 which receives step-by-step rotative movement in usual manner, as the builder frame is rocked. On the inner end of the shaft 9 is a beveled gear 11 which is operatively engaged with a bevel gear 12 secured to the lower portion of the screw shaft 13 having bearings in a block 14 at the top portion of the builder motion frame, and a block 15 at the lower portion thereof, the construction being such that as the pick wheel or ratchet 10 is turned step-by-step, the screw 13 will be gradually rotated.

A movable block 16 is threaded upon the screw 13 and its rear portion bears against the arm 2 of the builder motion frame, the construction being such that as the screw is rotated, the block 16 will be moved along the same. The block 16 is preferably limited in its movement in a downward direc-

tion by the projection 18 and the top of the block 15, and its raised position is defined by the screws 19.

Projecting at the sides of the block 16 are the side pieces 20 which extend beyond the sides of the upright 2 of the builder motion frame, and to each of these is secured one end of a strap or flexible connection 21 which passes down from said block and about rolls or guides 22 secured to the builder frame at the lower portion thereof. The other ends of said straps or flexible connections extend upward from said rolls or guides and are secured to a roll 23 mounted in suitable brackets 24 projecting from the upright arm 2 of the builder frame, the construction being such that if the block 16 starts downward from its upper position, the downwardly-extending flexible connections 21 will permit the roll 23 to turn contra-clockwise, viewing Fig. 2, and conversely, when the block 16 is moved upward the roll 23 will be turned in the opposite direction, as will be readily understood.

The ring-rail 25 is provided with downwardly-extending rods 26, as usual, provided with toes, such as 27, which rest upon the pins 28 extending from an arm 29, said arm being secured to a rocking sleeve 30 on a shaft 31, Fig. 1. The sleeve 30 has an arm 32 carrying a weight 33, and an arm 34 which is connected to the roll 23 by a flexible connection, the construction being such that the ring-rail is raised by the weight 33 and is lowered by the builder motion through the flexible connection.

The flexible connection between the roll 23 and rocking arm 34 may be variously formed, but as herein shown, it comprises a part 35 having one end secured to the roll 23 and its other end secured to a roll 36 having a cut-away portion 37 to which is secured one end of a chain or strap 38, Figs. 1 and 2, the other end being carried under a roll 39 from which leads the part 40 secured to the rocker arm 34. From the construction described, it will be noted that the weight 33 will lift the ring-rail in proportion as it is permitted to do so by the connection between the builder motion and rocker arm 34, and in order to modify this lifting action that a proper form of preliminary or initial winding or bunch be produced and a quick "get-away" be secured as such bunch is completed, that part of the flexible connection between the rolls 33 and 36 has secured thereto the deflector or finger 41.

The deflector or finger 41 may be of appropriate form and character as fully described in the application of Charles E. Lovejoy, before-mentioned; but in the present invention, it is associated with the Howard & Bullock builder motion modified and reorganized as hereinbefore described, so

that on starting the preliminary or initial windings, the block 16 being at the top portion of the screw 13, the flexible connection 21 passing downward about the rolls 22 and then to the roll 23, will cause said roll to be turned clockwise, Fig. 2, to the limit of such movement, so that the deflector or finger 41 will deflect or bend the connection 35 its maximum amount, and as the winding proceeds, the block 16 will descend, thus giving up the flexible connection 21, which, passing around the roll 23 to the right, Fig. 2, permits the weight 33 to turn said roll 23 contra-clockwise progressively and cause the deflector or finger to deflect the connection 35 less and less, as the ring-rail is raised in successive windings, until at the completion of the bunch or initial windings, the deflector or finger will be clear of the roll 23, which may for identification be known as the finger deflecting roll, and cease to deflect the connection 35, whereupon the regular traverse due to the builder motion, is resumed.

The cut-away roll 36 in connection with the deflector or finger 41 operating as described, enables a more rounded and desired character of bunch to be formed, substantially as pointed out in the application of Lovejoy, before-mentioned, such parts being adaptable to the Howard & Bullock type of machine by the reorganization and reconstruction as hereinbefore described.

The character of the filled bobbin and bunch produced, is well shown in Fig. 3, wherein the regular windings 42 cover the bunch 43, dotted lines, and the base portion of the filled bobbin is formed full and rounded.

What is claimed is:

1. In a spinning machine, the combination of a builder frame having an upright arm, a cam for rocking said arm, a screw carried by said arm, means for rotating said screw step-by-step, a block threaded on said screw, guide rolls mounted at the lower portion of said upright arm, a finger deflecting roll mounted at the top portion of said upright arm, flexible connections secured at one end to said block and passing downward therefrom about said guide rolls then upward to said finger deflecting roll, a ring-rail, flexible connections between the ring-rail and said finger deflecting rolls, and a deflecting finger carried by said flexible connections and adapted to be engaged and deflected by said finger deflecting roll.

2. In a spinning machine, the combination of a ring-rail, a builder motion comprising a rocking frame, having an upright arm, a cam for rocking said frame, a block movable downward from an initial position near the top of said frame as the latter is rocked, a finger deflecting roll carried at the upper portion of said upright arm, flexible connec-

tions between said movable block and said finger deflecting roll, guides for said flexible connection at the lower part of said upright arm for directing said flexible connections downward from said block, a flexible connection between said finger deflecting roll to the ring-rail, and a finger secured to said last-named flexible connection and adapted to be engaged by said finger deflecting roll during the building of a bunch and then to be disengaged therefrom.

3. In a spinning machine, the combination of a ring-rail, a weight for lifting said ring-rail, and a builder motion for controlling the lifting action of said weight comprising a rocking builder frame, a block carried thereby, means for moving said block toward the fulcrum of the rocking builder frame as the latter is rocked during the operation of the builder motion, a finger deflecting roll, a flexible connection between the said roll and ring-rail to control the lifting action of said weight, a finger secured to said flexible connection and adapted to be engaged by said roll to deflect the flexible connection during the building of a bunch and to be then disengaged therefrom, flexible connections between said block and said finger deflecting roll, and means for deflecting said flexible connections downwardly from the block and finger deflecting roll.

4. In a spinning machine, the combination of a ring-rail, a weight for lifting said ring-rail, and a builder motion for controlling the lifting action of said weight comprising a rocking builder frame, a block carried thereby, means for moving said block toward the fulcrum of the rocking builder frame as the latter is rocked during the operation of the builder motion, brackets carried at the upper portion of the builder frame, a finger deflecting roll carried by said brackets, flexible connections between said block and finger deflecting roll, guides for deflecting said flexible connections downward from said block as they pass to

said roll, a flexible connection between said finger deflecting roll and the ring-rail, and a finger carried by said flexible connection and adapted to be engaged and deflected by said finger deflecting roll during the building of a bunch and to be then disengaged therefrom.

5. In a builder motion, the combination of a rocking builder frame, a ring-rail, a weight for raising the ring-rail, a finger deflecting roll carried by the rocking builder frame, a flexible connection between said roll and ring-rail, a finger carried by said flexible connection and engaging said roll during the building of a bunch and then being disengaged therefrom, means carried by the rocking frame and movable along said frame step-by-step during the operation of the builder motion, and a flexible connection between said means and said finger deflecting roll for controlling the turning action of said roll by the said weight.

6. In a builder motion the combination of a rocking builder frame, a ring-rail, a finger deflecting roll carried by said rocking frame, a screw carried by the rocking frame, a block movable by said screw along said frame step-by-step during the operation of the builder motion, a flexible connection between said block and said finger deflecting roll to control the rotative movement of said roll, a flexible connection between the ring-rail and said finger deflecting roll, and a finger carried by said last-named flexible connection adapted to be engaged and deflected by said roll during the building of a bunch and to then be disengaged from said roll.

In testimony whereof, I have signed my name to this specification in the presence of two subscribing witnesses.

EMMERICH H. KRISTEK.
